UNITED STATES PATENT OFFICE.

HARRY D. HILDEBRAND, OF PITTSBURGH, PENNSYLVANIA.

VALVE.

1,229,455.

Specification of Letters Patent. Patented June 12, 1917.

Application filed May 4, 1916. Serial No. 95,332.

To all whom it may concern:

Be it known that I, HARRY D. HILDEBRAND, residing at Pittsburgh, in the county of Allegheny and State of Pennsylvania, a citizen of the United States, have invented or discovered certain new and useful Improvements in Valves, of which improvements the following is a specification.

The invention described herein relates to certain improvements in fluid pumps, the invention being especially applicable to pumps employed for compressing air and gases. The invention has for its object a valve formed of a thin flexible and preferably resilient strip of metal so arranged and supported as to be free to bend to uncover or open the port, and that the opening movement of each strip will be controlled or limited by an adjacent strip. The invention is hereinafter more fully described and claimed.

In the accompanying drawings forming a part of this specification, Figure 1 is a top plan view of the improved valve mechanism, Figs. 2, 3 and 4 are sectional views, the planes of section being indicated respectively by the lines II-II, III-III, and IV-IV, Fig. 1; Figs. 5, 6, 7, 8 and 9 are views similar to Fig. 1, and illustrate respectively certain different embodiments of the improvements claimed herein; Fig. 10 is a sectional view on a plane indicated by the line X-X Fig. 7, and Figs. 11 and 12 are top plan views of further modifications of the improved valve mechanism.

In the practice of my invention, the valve block 1 which may be of any peripheral contour, is provided in its faces with grooves 2 of a suitable width and depth. These grooves may be arranged radially as shown in Figs. 1, 5, 6 and 11, or may be substantially parallel with each other as shown in Figs. 7, 8, 9 and 12. The ports 3 for the passage of the fluid are formed in the side walls of the grooves, so that there will be two ports discharging into each groove. The metal wings, 4 and 5, which serve as valves to prevent any reverse flow of the fluid, are made of thin pieces of metal, preferably spring steel and of a length and width greater than the corresponding dimensions of the ports. The wings which are arranged to bear against opposite sides of each groove, are supported in such manner

that while entirely free to flow or bend as fluid is forced through the ports, they will spring back to closed position. It will be observed that the wings in each groove move toward each other in their opening movements, and in order to prevent injurious degree of flexure, the grooves are made of such a width that the wings will meet and bear one against the other, before either has been bent to an injurious extent.

The wings in each groove may be made separate and independent one of the other, as shown in Fig. 11, or may have adjacent ends integrally connected as shown in Fig. 12. In Figs. 1, 5, 6, 7, 8 and 9, is shown what is styled the hairpin shape, the ends of the wings being so constructed and arranged that the flexure of either wing effects the flexure of the other. In the construction shown in Fig. 9, adjacent ends of the wings are formed with hook shaped portions *a*, the portion *a* on one wing as fitting around a pin 6 and within the corresponding part of the other wing 4. It is preferred, however, that the oppositely disposed wings 4 and 5 have two adjacent ends, and preferably the inner ends, integrally connected, and the connecting portion so bent that the respective wings will bear against opposite sides of the groove due to the resilience of the connecting portion, as shown in Figs. 1, 5, 6 and 7. While the movement of the wings along the grooves may be prevented by any suitable means, such movement can be conveniently prevented by pins 6, which are preferably made of sufficiently small diameter as not to limit the opening movement of the wings. Upward movements of the wings are prevented by a disk 7 held in place by the screw 8. This disk is made of such diameter as to overlap the inner ends of the wings, but will bear on the pins 6, which project slightly above the edges of the wings. The wings are supported by raised portions 9 in proper relation to ports 3, and in such manner that their lower edges, or at least the major portions thereof, will be out of contact with the bottoms of the grooves 2, as shown in Figs. 2, 3, 4 and 10. It will be observed that in the several constructions, only those portions having small movements, when the wings are shifted, bear upon the raised portions 9.

It will be seen by reference to Fig. 1, the

fluid flowing through passages or recesses 10 divides and escapes through ports 3 opening into adjacent grooves, so that wings in the same groove are pushed toward each other and will strike one against the other as shown by dotted lines in Figs. 1, 5, 7 and 8. As both will be subjected to substantially equal but oppositely acting pressures, each will act as a stop to prevent further movement of the other.

In lieu of employing pins 6 for supporting the wings, the inner ends of the plateaus 11, or bodies of metal intermediate adjacent grooves, may be constructed to serve as bearings for the closed ends of the hair-spring form of valves as shown in Fig. 5. When such construction is employed, one wing of a pair will be arranged in one groove and the other member of the pair in an adjacent groove, and the flow from both ports, connecting with a common passage or recess 10, will be controlled by wings integrally connected at their inner ends. In the construction shown in Fig. 1, the members of a pair are forced toward each other, and one serves as a stop for the other, while in the construction shown in Fig. 5, a wing of one pair is moved toward a wing of another pair, and the wings of adjacent pairs will operate as stops, the one for the other.

In Fig. 6 is shown a construction having both wings of one pair in a groove, while the grooves on both sides of the latter, have arranged therein a wing 4 of one pair and the wing 5 of the other pair. In this construction, pins 6 serve as bearings for the loop portion of one pair, and the loop or connecting portion of this pair serves as a bearing for the pair having wings in separate grooves.

As shown in Figs. 7, 8, 9 and 11, the grooves may be made parallel and extend across the valve block, and if desired, one wing may be made longer than the other and this extension 12 be bent around, so as to bear against the other wing as shown in Fig. 8. In this construction each wing will be bent or flexed for its entire length, the flexure being distributed with approximately uniformity. This distribution of the resilience along the wings renders it possible for the wings to withstand a greater pressure. That is the wings are rendered more rigid without any increase in the thickness of the material employed. The same end may be attained by employing an integral construction, *i. e.*, integrally connecting both ends of the wings as shown in Fig. 12. As shown in Fig. 11, the wings or valves may be made independent of each other, in which case their end portions bear against pins 12 arranged adjacent of opposite ends of the grooves. In lieu of employing pins for preventing movements of the wings, longitudi-

nally of the grooves, rings 13 may be placed 65 around a raised portion of the block as shown in Figs. 11 and 12.

No claim is made herein to the construction shown and described in application No. 95333, filed May 4th, 1916. 70

I claim herein as my invention:

1. A valve mechanism for pumps having in combination two resilient valves adapted to move in opposite directions in their opening and closing movements, each valve being 75 controllable by the other as regards its opening movement.

2. A valve mechanism for pumps having in combination two oppositely arranged ports, valves controlling said ports, each 80 valve being adapted to serve as a stop to limit the opening movement of the other.

3. A valve mechanism for pumps having in combination two oppositely arranged ports, resilient wings adapted to normally 85 close said ports, and to operate as stops, the one for the other, as regards their opening movements.

4. A valve mechanism for pumps having in combination two oppositely arranged 90 ports, two valves yieldingly held in closed position and adapted to be operated by oppositely applied fluid pressure, and to abut the one against the other in their opening movements.

5. A valve mechanism for pumps having in combination two oppositely arranged ports, two normally closed resilient valves, adapted to be shifted to open position and into the range of movement of each other 100 by oppositely applied fluid pressure.

6. A valve mechanism for pumps having in combination two oppositely disposed ports, two resilient wings arranged to normally close said ports, and having portions 105 of their ends curved to engage a fixed abutment, whereby said wings are held as against longitudinal movement.

7. A valve mechanism for pumps, having in combination a valve block provided with 110 a groove and having ports in the opposite walls of the groove, valves of thin resilient strips of metal normally closing said ports, the distance between the opposite sides of the grooves being so proportioned as regards the desired maximum opening movements of the valves, that each valve will operate as a stop to limit the opening movement of the other valve.

8. A valve mechanism for pumps having 120 in combination a valve block provided with a groove and having ports in the opposite walls of the groove, a hair-pin shaped strip of resilient metal arranged in said groove with the wings bearing against the opposite 125 walls of the groove and an abutment bearing against the closed end of the hair pin.

9. A valve mechanism for pumps having

in combination a valve block provided with a plurality of grooves and having ports in the opposite walls of the grooves, hair-pin shaped strips of resilient metal, having their 5 wings arranged in said grooves and normally closing the ports opening into the grooves, each of the wings in each groove be-

ing adapted to limit the opening movement of the other wing in the same groove.

In testimony whereof, I have hereunto set 10 my hand.

HARRY D. HILDEBRAND.

Witness:

G. G. TRILL.
